AUTOMOBILE TROUBLE FLASHER

Theodor Box, 1188 Albee Road,
Brielle, N.J. 08730

Filed Oct. 17, 1974, Ser. No. 515,538

Term of patent 14 years

Int. Cl. D10—06

U.S. CL. D10—114

Ti q.1.

Ti q.2.

FIG. 4

FIG. 5.

FIG. 1 is an isometric view of an automobile trouble flasher showing my new design as taken from the front and side;

FIG. 2 is an isometric view thereof as taken from the rear and side;

FIG. 3 is a side elevational view as seen from the left of FIG. 1;

FIG. 4 is a top plan view thereof; and

FIG. 5 is a rear elevational view thereof.

The flasher is translucent and shaded to indicate contrast.

I claim:

The ornamental design for an automobile trouble flasher, substantially as shown and described.
